UNITED STATES PATENT OFFICE.

LEO O. GAGNON, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

EYE-PROTECTOR.

1,265,647.

Specification of Letters Patent.

Patented May 7, 1918.

Application filed October 13, 1917. Serial No. 196,408.

To all whom it may concern:

Be it known that I, LEO O. GAGNON, a citizen of the United States, residing at Southbridge, in the county of Worcester and State of Massachusetts, have invented certain new and useful Improvements in Eye-Protectors, of which the following is a specification.

This invention relates to improvements in eye protectors, and has as one of its principal objects the provision of an improved form of eye protector which shall be readily adjustable to suit the particular requirements of the individual wearer thereof.

A further object of the present invention is the provision in connection with an adjustable bridge eye protector, of a crest pad or nose bearing rest and of improved adjustable connection between the crest pad and the bridge, facilitating ready relative adjustment of the several parts as desired.

Another object of the invention resides in the simplification of the construction of devices of this character and in the provision of an improved structure embodying a minimum number of parts and soldered connections, thus to the greatest possible degree eliminating any possibility of loosening of the parts or undue softening thereof by repeated soldering operations of the like.

Other objects and advantages of my improved construction should be readily apparent by the following specification taken in connection with the accompanying drawings forming a part thereof, and it will be understood that I may make any modifications in the specific details of construction shown and described within the scope of the appended claims without departing from or exceeding the spirit of my invention.

Figure I represents a front view of my improved structure.

Fig. II represents a similar view showing the parts in more widely separated relation.

Fig. III represents a front view of a slightly modified construction.

Fig. IV. represents a similar view of another modification thereof.

In the drawings, in which similar characters of reference are employed to denote corresponding parts throughout the several views the numeral 1 designates the lenses

of the protector, inclosed in the usual rims or frames 2, provided with the end pieces 3 for the retaining temples 4, and being centrally connected as by my improved bridging member.

Referring to that form of construction illustrated in Figs. I to III inclusive, the entire bridging member is shown as formed from a single piece of material, whose course for convenience will be traced from left to right. The material, which is preferably a fairly rigid yet pliable wire, is attached to the left hand frame, as at 5, and extends directly across the frame in the portion 6, and downwardly in the portion 7, the two together forming a substantially L-shaped member secured to the right hand frame at the terminus of the L, the material from this point being continued inwardly and upwardly in the inverted U loops 8 which terminate in a second loop 9 having its point or lower portion secured as by soldering to the crest pad or nose rest 10, the remaining portion of the material being a duplicate of that just described but disposed on the opposite side of the mounting and comprising the second inverted U-shaped loop 11 attached at its terminus as at 12 to the left hand rim, and extending upward in the L-shaped member comprising the arms 13 and 14, corresponding to the arms 6 and 7 and the opposite terminus being secured to the right hand frame.

By reference to the drawings it will thus be seen that the lens frames are particularly connected as by the pair of oppositely disposed L members extending substantially diagonally between the lenses and immediately crossing each other and are additionally connected by the substantially M-shaped central wire looped member, which looped member bears at its lower end the nose crest pad 10. The advantages of this construction should be apparent by a comparison with Figs. I and II, from which it will be seen that when it is desired to separate the parts it is merely necessary to draw them apart, when the L members will be given a more obtuse angle, while the loops 8 and 11 will be opened out somewhat. Additionally, it will be noted that the central depending loop 9 bearing the nose rest, forms substantially a supporting post for the rest, and that by forward or rearward flexing or bending of this post,

or lateral bending if desired, the exact position of the nose rest 10 may be adjusted and regulated as desired.

In Fig. IV, I have illustrated a slight modification of my invention, in which in place of the depending loop 9 for the crest pad the loop is split into two separate arms which are secured to the pad near its end, in place of centrally, the other adjustment loops, etc., of the structure being the same and the general function and operation being identical.

I claim:

1. In an eye protector, the combination with a pair of lens rims, of a substantially M-shaped member connecting the rims and having its ends secured thereto, and a nose bearing pad secured to the central leg of the M and adjustable by bending of said 20 leg.

2. A device of the character described, including lens rims, oppositely disposed L-shaped members having their termini secured to opposite rims, and a central member comprising a pair of upwardly extending loops connected by a central depending loop, said central member being integral with the 25 L-shaped members at their lower points of

attachment to the lens rims and having a crest pad secured to the depending loop whereby said depending loop automatically centers the pad on relative adjustment of the lens rim and allows of independent adjustment of the pad by bending of the central looped member.

3. An eye protector, comprising diagonally disposed adjustable cross members, lens rims secured to and connected by said cross members, and an inverted U-shape looped pliable member extending inwardly from each of the lens rims and having its inner end secured to a crest pad, substantially as illustrated.

4. An eye protector, comprising diagonally disposed adjustable cross members, lens rims secured to and connected by said cross members, and a looped pliable member extending inwardly from each of the lens rims and having its inner end secured to a crest pad, substantially as illustrated.

In testimony whereof I affix my signature in the presence of two witnesses.

LEO O. GAGNON.
